ASA M. BEARD, OF HILLSBOROUGH BRIDGE, NEW HAMPSHIRE, ASSIGNOR
TO HIMSELF AND SOLOMON McNIEL, OF SAME PLACE.

Letters Patent No. 60,847, dated January 1, 1867.

IMPROVEMENT IN HEAD BLOCKS FOR SAW-MILLS.

The Schedule referred to in these Letters Patent and making part of the same.

TO ALL WHOM IT MAY CONCERN:

Be it known that I, A. M. BEARD, of Hillsborough Bridge, Hillsborough county, and State of New Hampshire, have invented a new and improved Log Carriage for Saw Mills; and I do hereby declare that the following is a full, clear, and exact description thereof, which will enable others skilled in the art to make and use the same, reference being had to the accompanying drawing, forming part of this specification, in which—

Figure 1, sheet 1, is a front elevation of my improved log carriage; and

Figure 2 is a top plan of the same.

Figure 3, sheet 2, is a cross-section, taken in the line xx , fig. 2.

Figures 4, 5, 6, and 7 are detail views of important parts.

Similar letters of reference in the different figures indicate corresponding parts.

This invention consists in certain new and useful improvements in log carriages whereby the log is secured and handled in an easy and rapid manner; and also in an index of novel construction, which determines without calculation where the saw should enter the log in making the first cut, saving time and labor, as hereinafter explained.

A $A'a'a$, figs. 1, 2, and 3, is the carriage, and B is the rest, sliding laterally thereon; the rest, B, has two arms, $b b$, fig. 2, projecting from its rear side, and these arms carry a shaft, C, fig. 2, which has a pinion, c , upon each end. These pinions, c , engage each with a mortise rack, a^2 , formed in the top of the angular bed-pieces or slides a ; and by means of the said mortise racks $a^2 a^2$, pinions $c c$, and shaft C, the rest, B, is carried back and forth on the slides, $a a$. The shaft, C, is operated by a ratchet-lever, D, which has a double pawl or ratchet, d , which engages with a cog-wheel, E, the said cog-wheel E acting as a ratchet-wheel for the lever and pawl $D d$, and also as a cog-wheel, upon which, a pinion, e , (fig. 1,) may act to run the rest B back when a log is cut up and when another one is to be received on the carriage. The pinion e is operated by a hand crank, f , on the shaft F. By means of this crank and pinion e the rest E is run back in less time than it can be done with the ratchet-lever D, although the said lever D has facilities for moving the rest B backward as well as forward, which is convenient in setting the log properly before the saw. The rest B is secured in place by a hook-shaped pawl, g , the said pawl being pivoted to the rest at g' . The double ratchet or pawl d is suspended on the lever D (fig. 6) by a pivot, h , in its centre; a spring-lever, I, is also pivoted to the lever D by a pivot, i . The lower end of this lever I enters a notch in the upper side of the double ratchet, and its upper end is bifurcated, and embraces a cam-wheel, G, which is pivoted to the top of the lever D, the said cam-wheel G having a handle, H, (fig. 1,) by which it may be turned; and as the cam G (fig. 6) is thrown to either side, the lever I tilts the double ratchet d , so that one of its ends is lowered into connection or engagement, and the opposite end is raised out of action; and by these means the pawl d is readily controlled, and made to give either a backward or forward movement of the rest, as desired. Outside of the cam G is a second cam, j , (fig. 1,) which is attached to g and moves therewith; and this cam or eccentric j raises and lowers or operates a connecting-rod, J, which takes hold of the pawl g by a hook on its lower end; and as the handle H and eccentric or cam G are turned into position for running back the carriage, the eccentric j and rod J elevate the hooked pawl g out of action, and the rest is free to run back. x (fig. 1) is a spring, which presses the eccentric or cam G against the lever D, and holds the cams in position by friction. The throw of the lever D is regulated so as to give any required distance of movement to the rest B necessary for board sawing, by a fixed stop, k , and an adjustable stop, K, (fig. 2.) The adjustable stop K slides on a graduated arm, N, and is secured in position by a sliding pawl, l , (fig. 5,) which engages with the notches n (fig. 2) in one edge of the arm N, the pawl l being held into the notches by a spring, L, (fig. 5,) and is operated by a knob, m . The arm N is graduated on its upper face, and marked with figures, so that it can be seen at a glance where to set the adjustable stop K to give the proper space between the stops for the lever D to move in and give the desired throw for the requisite thickness of boards. The rest B is provided with three stands O M O, (figs. 1 and 3,) the centre one, M, being fixed, and the end stands, O O, being movable, so that either of them may be pushed out for carrying the small end of a tapering log into line with the saw. These movable stands O slide in guides $p p$, (figs. 1 and 2,) shafts Q Q, and pinions $s s$; which

are indicated by dotted lines S S in fig. 1, the said pinions α engaging each with a toothed rack on the bottom of the horizontal part O' of the stands O. These stands O operate independently of each other, one of the ratchet-levers R moving one of them and the other lever R the other. The ratchet-levers R for operating the stands have the double ratchets, and also the hooked pawl, and all of the devices for controlling them, the same as the rest-moving lever D, already explained. The levers R are held in any position in which they are placed by pawls 11, (fig. 3,) which engage with a rack, 12. The stands O are each provided with a roller, q, which is pivoted near its top and so as to project slightly upward beyond the top of the stand, to prevent wide boards, when edging them on top of a log, from catching on the top of the said stands as they are removed. The end stands O O have dogs or spurs T T, (figs. 2 and 3,) which slide in guides attached to the stands, and they are driven into the log to secure it in position. The bar or body portions of these dogs are notched, and a pawl, Z, (fig. 3,) is pivoted to each stand in such a position that when the dogs are driven the said pawls engage with the notches in the bar and prevent them from working out of the log. The pawl Z is elbow-shaped, and it is suspended to the stand O by a pivot in its centre, in such a manner that when the pawl end is down, as shown, then the weight of the pawl, as a whole, is principally on that side of the pivot; but when the pawl is thrown up, it is held there by the preponderance of weight being thrown behind the suspending pivot, the upper or rear arm of the pawl acting as a counterbalance, so that the pawl end is held up after only a slight elevation or movement. A screw-dog, U, (figs. 1, 2, and 7,) is also provided for holding the log snug in position. This dog is mounted in a frame, Y, which fits on to the rest B, (fig. 7,) and is thrown into the log by depressing the lever V, which forces the screw-spur U in contact with the log, and then the screw is bedded in the log by turning its crank-handle u. The elbow-lever V is pivoted at v, and its short arm connects with dog by occupying the groove w in the said dog or spur U. When not in use the spur is held back by a spring, W, which holds up the lever V. The log-rest or slide a' (fig. 2) has on one side and at its rear end a toothed rack, 1; this rack is fixed. The rest B carries in its rear a vertical shaft, 5, (fig. 3,) which has on its lower end a pinion, 2, (fig. 2,) which engages with the rack 1. To the upper end of the vertical shaft 5 is fixed a disk, 4; which has its periphery graduated and marked off with figures; and above this disk is a second one, 3, which is loose on the shaft 5, and is graduated like the fixed disk 4, only it has three graduations, arranged one above the other, and each scale or graduation being divided off, so that the spaces between the marks are of different lengths. 6 and 7 (fig. 1) are index hands, or pointers, the lower one, 7, pointing for the lower disk, and the upper one, 6, pointing for the loose upper disk. The upper pointer 6 is adjustable on the standard 8. The sleeve of this pointer fitting over the standard has a nib, which engages with one of a series of notches, 9, in one edge of the standard 8; and this nib is held into the notch in which it is placed by a spring, 10. This adjustable pointer 6 is adjusted on the standard 8 so as to point to the particular graduation of the series on disk 3 which is being used. As the rest B is being moved the fixed rack 1 (fig. 2) turns the shaft 5 (fig. 3) and the graduated disks 4 and 3. The fixed disk 4 is spaced off, so as to show at all times the distance between the rest B and the saw in inches. When sawing a log into boards, and when a plank or timber of a certain thickness is to be left next to the rest B, then the adjustable index 3 is used, as follows: A point in the board column on the index 3 is turned directly above the figure on index 4, which represents in inches the thickness of the plank or timber to be left, and then the saw is started into the log by the said board column on the index 3; and this brings the saw out correctly at the required point for leaving the desired size of timber after the first part of the log has been cut up into boards. The required thickness of the boards in this latter case determines which of the three graduations on index 3 is to be used. If the lower graduation on 3 is marked for inch and a quarter boards, and this is the thickness of boards required from the first part of the log, and if the piece of timber to be left is to be five inches in thickness, then any of the inch and a quarter marks in the lower graduation of 3 is turned opposite to the figure 5 on the lower index, and the saw is started on the outside of the log by the lower graduation on 3, and the log is cut up into the required stuff; and by these means the log is brought to the right point before the saw at once and without calculation, thus making an important saving in time and labor.

Having thus described my invention, what I claim as new, and desire to secure by Letters Patent, is—

- I. I claim the rotating index 4, supported on and carried by the log rest B, and operated by a fixed rack, 1, and pinion 2, substantially as and for the purpose herein specified.
- I. I claim, in connection with the graduated indicating disk or index 4, pinion 2, rack 1, and log rest or head block B, an adjustable secondary index or graduated disk, 3, arranged and operating substantially as and for the purpose explained.
- I. I claim a hand lever, D, having a double pawl, d, which is controlled by an eccentric, G, and sub-lever, I, pivoted thereto, and having a second eccentric or cam, j, and rod J, for lifting the head block or rest pawl, g, in connection with a spur-wheel, E, pinions c c, racks α^2 , and rest B; as and for the purpose shown and explained.
- I. I claim the balanced elbow-shaped pawls Z, in connection with the stands O and sliding dogs T, as and for the purpose described.
- I. I claim the rollers q, pivoted to the tops of the stands D, as and for the purpose set forth.
- I. I claim the stands D, in combination with the movable rest B, when the said stands are adjustable on the said rest B, substantially as and for the purpose set forth.

ASA M. BEARD.
